[57] CLAIM

The ornamental design for a ornamental decoration for a sports shoe, as shown and described.

DESCRIPTION

FIG. 1 is a perspective view showing my new design for an ornamental decoration for a sports shoe, illustrated as part of a shoe, the dotted lines being for illustrative purposes only and forming no part of the claimed design;

FIG. 2 is an enlarged front view of the ornamental decoration thereof;

FIG. 3 is a top plan view thereof;

FIG. 4 is a bottom plan view thereof;

FIG. 5 is a right side view thereof; and,

FIG. 6 is a left side view thereof.

The rear view not shown is plain and unornamented. The broken lines shown on the claimed design represent top stitching.

FIG. 1

FIG. 2

FIG. 3

FIG. 4

FIG. 5

FIG. 6
